SECTIONAL BOILERS

Anthony J. Donohue, Merion, Pa.

Application August 13, 1956, Serial No. 603,545

6 Claims. (Cl. 122—225)

This invention relates to sectional boilers for steam and hot water heating which are also suitable for supplying hot water for domestic consumption.

In recent years the biggest buyers of small homes heating boilers have been builders of new developments. This market is extremely competitive and has resulted in the inability of small cast iron boilers to compete with the newer small steel boilers. This situation is due in part to higher performance standards set by manufacturers of cast iron boilers and in part to the design adaptability of small steel boilers to supply satisfactory domestic hot water service in addition to the heating requirements without appreciably increasing the cost of manufacture. While cast iron boilers can perform this dual service, their construction heretofore has made it relatively more difficult and costly to add the domestic hot water heater to the boiler.

In my prior application filed July 20, 1956, Serial No. 599,040, there is shown and described a boiler constructed in an improved manner and in which tankless heaters can be installed with successful performance in smaller cast iron boilers than has heretofore been possible.

As shown and described in said application a vertical flueway sectional boiler is provided consisting of a front section and a back section with a single vertical flueway therebetween for the absorption of heat and the discharge of the products of combustion.

The successful operation of a tankless hot water heater requires a minimum input rating of the order of one gallon per hour of oil or 120,000 B.t.u. per hour of combustible gas. Such input can be expected to provide domestic hot water at the rate of 3 gallons per minute at an average temperature rise of 100 degrees F. for a period of five minutes. Such a domestic hot water draw generally meets the requirements of single family homes because a rapid recovery rate, of the order of about three to four minutes, is expected with such heaters.

In houses of the ranch type with relatively low height chimneys reduction of temperature of the gases of combustion to meet boiler code requirements (generally 600° F. or less) and successful venting of the products of combustion with extremely small draft loss through the boiler imposes severe design restrictions, particularly if the flueway has a width of about 18 inches.

If at the same time, the boiler is further accommodated for table top height, with an overall height limitation of boiler casing of about 36 inches and with only about twelve inches of flueway, the design problem is made even more difficult of solution.

In my prior application for patent above identified, there is disclosed a construction in which, by the elimination of the push nipple boss at the top of the flueway, theretofore considered essential, a substantially unobstructed flueway was provided so that the boiler was capable of meeting the capacity and design requirements referred to above.

The operation of a boiler with such a flueway can be

2

further enhanced if the bottom of the flueway is constructed as hereinafter described.

It is the principal object of the present invention to provide a boiler construction with which an improved flueway entrance is provided having increased heat transfer surfaces, whereby the draft loss is reduced at the critical transition location between the combustion chamber and the flueway, and the combustion and the heat absorption at the transition location are greatly improved.

It is a further object of the present invention to provide a cast iron sectional boiler which overcomes the objectionable features heretofore encountered, particularly in small sizes of boilers.

It is a further object of the present invention to provide a cast iron sectional boiler having a front boiler section and a rear boiler section with a single vertical flueway therebetween and in which the flueway has an improved entrance construction.

It is a further object of the invention to provide a cast iron sectional boiler having a front boiler section and a rear boiler section with a single vertical flueway therebetween in which the flueway has an improved entrance construction which reduces draft loss at this critical location without sacrificing the provision of adequate heat transfer surfaces, including projections, at this location.

Other objects and advantageous features of the invention will be apparent from the description and claims.

The nature and characteristic features of the invention will be more readily understood from the following description taken in connection with the accompanying drawings forming part thereof, in which:

Figure 1 is a vertical central sectional view of a boiler in accordance with the present invention;

Fig. 2 is a vertical sectional view taken approximately on the line 2—2 of Fig. 1;

Fig. 3 is a horizontal sectional view taken approximately on the line 3—3 of Fig. 1;

Fig. 4 is a fragmentary sectional view, enlarged, taken approximately on the line 4—4 of Fig. 1.

It should, of course, be understood that the description and drawings herein are illustrative merely, and that various modifications and changes can be made in the structure disclosed without departing from the spirit of the invention.

Like numerals refer to like parts throughout the several views.

The sectional boiler, in accordance with the present invention includes a plurality of vertically disposed cast iron sections in facing relation with an interiorly disposed combustion space or chamber, supplied with fuel for combustion therein, and with a vertical flue between adjoining sections for heat exchange and discharge of products of combustion.

The boiler sections can be connected and held together at the bottom by threaded nipples and can also be connected and held together at the top by a removable head, as shown in my prior application referred to above, which head has hot water delivery and air vent connections and can serve if desired, as a support for submerged domestic water heating coils, for a flow control valve and for a temperature responsive element.

Referring now more particularly to the drawings, a pair of aligned and meeting sections 12 and 13 of a cast iron sectional boiler substantially table top height or less are shown which may constitute the front and rear sections. The sections 12 and 13 and the water spaces therein can be connected at the top thereof by a connecting head 14 from which a flow pipe 14a or 14a' extends for the delivery of heated water to the heating system.

The front section 12 is provided with a substantially

straight vertical front wall 15, vertical side walls 16 and 17 extending rearwardly therefrom, a horizontal bottom wall 18 extending rearwardly from the front wall 15 and connected to the side walls 16 and 17, and a horizontal bottom wall 18 extending rearwardly from the front wall. An intermediate vertical wall portion 23 is provided in spaced parallel relation to the front wall 15 to provide a separating wall between the upper part of the water space of the front section and a vertical flue passageway 25. The wall portion 23 has a plurality of spaced horizontal projections 24, including a lower row 24', extending therefrom and into the flue passageway 25 and providing extended heat exchanging surfaces. The side walls 16 and 17 provide the side boundaries of the flueways 25.

The front section 12 also has interiorly disposed and below, and in communication with the flue passageway 25, the front part of a combustion chamber 26.

A burner opening 27 extending through the front wall 15 and into communication with the combustion chamber 26 can be provided for the insertion of a burner tube 28 for supplying gas or liquid fuel, and air for supporting combustion.

The rear section 13 is substantially similar in construction to the front section 12, although of opposite hand, with a vertical rear wall 15a, vertical side walls 16a and 17a disposed in aligned and meeting relation to the side walls 16 and 17 in the assembled condition of the sections 12 and 13, a horizontal bottom wall 18a, a top wall 19a and an inner rear wall 15' spaced from the wall 15a to provide water circulation and a rear water wall for the combustion space 26.

An upper intermediate wall portion 23a similar to the wall portion 23 with spaced projections 24a, and a lower row 24a', extending therefrom and in registered relation to the projections 24 and 24' in assembled condition of the sections 12 and 13. The rear part of the combustion chamber or space 26, aligned with the front part thereof, is provided in the rear section 13 and is bounded at the rear by the wall 15'. The combustion chamber 26 can be lined with refractory material, if desired, when the boiler is oil fired.

The combustion chamber 26 and the vertical flue passageway 25 thereabove are in communication through what can be referred to as a transition section or zone and in accordance with the invention and to provide the transition section or zone the sections 12 and 13 have transverse horizontal wall portions 50 and 50a with transverse vertical wall portions 51 and 51a extending upwardly therefrom to aligned horizontal wall portions 52 and 52a. The wall portions 52 and 52a are connected respectively to the portions 23 and 23a. At spaced locations the wall portions 51 and 52 and 51a and 52a have extending therefrom fins or ribs 53 and 53a which face downwardly towards the combustion space 26, extend in a direction from front to rear, and provide extended surfaces for heat absorption from the hot gases of combustion. Intermediate the ribs 53 and 53a, inclined walls 54 and 54a are provided connected by vertical walls 55 and 55a to the wall portions 23 and 52 and 23a and 52a to provide inclined entrance passageways between the combustion chamber 26 and the flue passageway 25. This increases the entrance area to the flue passageway, provides an improved character of combustion and of gas flow, and reduces the draft loss heretofore occasioned upon the movement of the gases from the combustion chamber 26 to the passageway 25. An improved character of heat transfer also occurs at this location and is aided by the lower row of projections 24' and 24a' and the ribs 53 and 53a. The ribs 53 and 53a aid in guiding the gases into the passageway 25. The gases from the passageway 25 can be discharged by a collecting hood 62, carried on the top walls 19 and 19a and with a flange 63 for the attachment of a pipe (not shown) leading to the stack.

In use, the hot gases of combustion rise in the combustion chamber 26, contact and are guided and directed by the walls 50, 50a, 51, 51a, 52, 52a and the fins 53 and 53a and the walls 54, 54a, 55 and 55a into the passageway 25 between the walls 23, 16 and 17, and 23a, 16a, and 17a, and pass from the top of the passageway 25 for discharge.

The gases of combustion, by their contact with the exposed surfaces of the combustion chamber 26 and the passageway 25, and with the fins 53 and 53a and the projections 24, 24' and 24a and 24a', give up a large portion of their heat content for heating the water in the broiler, so that the temperature of these gases is reduced to permissible and desired levels while the draft loss is kept to a minimum.

Adequate heat is transferred to the water in the boiler to provide, within the rated capacity, for the heating system and for domestic hot water.

I claim:

1. A liquid heating boiler having walls enclosing a liquid space, an interiorly disposed combustion chamber at the lower part of said walls and a flueway of lesser cross section extending therefrom to the top of said walls and having spaced vertical boundary walls, a transition section between said combustion chamber and said flueway at the lower portion of said flueway, said transition section including a plurality of spaced flueway lining wall portions with upwardly extending parts aligned respectively with the flueway walls and transverse parts connected to said upwardly extending parts and facing towards said combustion chamber, spaced heat exchanging members extending transversely from said upwardly extending parts into said flueway and disposed in the path of the gases directed by said flueway lining portions, additional lining wall portions interposed between said first lining wall portions and having parts inwardly inclined with respect to said boundary walls for guiding the combustion gases from the combustion chamber into the flueway, and additional heat exchanging members spaced above and offset with respect to said first mentioned heat exchanging members and disposed in the path of the gases directed by said inclined parts.

2. A boiler as defined in claim 1 in which said transverse parts have heat exchange fins extending therefrom and facing towards said combustion chamber.

3. A sectional liquid heating boiler comprising a plurality of separate connected vertical liquid heating boiler sections each with enclosing walls, said sections being disposed in facing relation and having therebetween a combustion chamber and a gas discharge passageway having spaced vertical boundary walls extending upwardly from said combustion chamber, a transition section between said combustion chamber and said gas discharge passageway at the entrance of said passageway, said transition section including a plurality of spaced flueway lining wall portions with vertical parts aligned with the passageway walls and horizontal parts connected to said vertical parts and facing downwardly towards said combustion chamber, spaced heat exchanging members extending transversely from said vertical parts into said passageway and disposed in the path of the gases directed by said flueway lining portions, additional lining wall portions interposed between said first lining wall portions and having parts upwardly and inwardly inclined with respect to said passageway walls for guiding the combustion gases from said combustion chamber into the passageway, the interior faces of said lining wall portions being exposed in the interior of said boiler sections to the liquid to be heated, and additional heat exchanging members spaced above and offset with respect to said first mentioned heat exchanging members and disposed in the path of the gases directed by said inclined parts.

4. A sectional liquid heating boiler comprising a plurality of separate connected vertical boiler sections each with enclosing walls, said walls enclosing said sections

being disposed in facing relation and having interior walls therebetween providing a combustion chamber and a vertical gas flueway extending upwardly from said combustion chamber in heat exchange relation to said sections, an integral transition section between said combustion chamber and said flueway in the bottom of said flueway, said transition section including a plurality of horizontally spaced flueway lining wall portions with vertical parts aligned respectively with the flueway walls and horizontal parts connected to said vertical parts and facing downwardly towards said combustion chamber, spaced heat exchanging members extending transversely from said vertical parts into said flueway and disposed in the path of the gases directed by said flueway lining portions, additional lining wall portions interposed between said first lining wall portions and having parts upwardly and inwardly inclined with respect to said flueway walls for guiding the combustion gases from the combustion chamber into the flueway, and additional heat exchanging members spaced above and offset with respect to said first mentioned heat exchanging members and disposed in the path of the gases directed by said inclined parts.

5. A sectional liquid heating boiler comprising a front and a rear vertical boiler section each having a horizontal top wall, parallel vertical front and rear walls, and parallel vertical side walls, said sections being disposed in facing relation with their side walls in alignment and having spaced vertical wall portions parallel to said front wall and providing with said side walls a vertical flue, said boiler sections having interior liquid heating spaces and having disposed therebetween and below said flue a combustion chamber, a transition section between said combustion chamber and said flue, said transition section including spaced flue lining wall portions with vertical parts respectively aligned with the flue walls horizontal parts connected to said vertical parts and facing downwardly towards said combustion chamber, spaced heat exchanging members extending transversely from said vertical parts into said flue and disposed in the path of the gases directed by said flue lining portions, additional lining wall portions interposed between said first lining wall portions and having parts upwardly and inwardly inclined with respect to said flue

40

walls for guiding the combustion gases from the combustion chamber into the flue, and additional heat exchanging members spaced above and offset with respect to said first mentioned heat exchanging members and disposed in the path of the gases directed by said inclined parts.

6. A sectional liquid heating boiler comprising a front and rear vertical boiler section each having a horizontal top wall, parallel vertical front and rear walls, and parallel vertical side walls, said sections being disposed in facing relation with their side walls in alignment and having spaced vertical wall portions parallel to said front wall and providing with said side walls a vertical flueway, said boiler sections having interior liquid heating spaces and having disposed therebetween and below said flueway a combustion chamber, and a transition section interposed directly between said combustion chamber and said flueway, said transition section including spaced flueway lining wall portions with vertical parts respectively aligned with the flueway wall portions and horizontal parts connected to said vertical parts and facing downwardly towards said combustion chamber, spaced heat exchanging members extending transversely from said vertical parts into said flueway and disposed in the path of the gases directed by said flueway lining portions, additional lining wall portions interposed between said first lining wall portions and having parts upwardly and inwardly inclined with respect to said flueway wall portions for guiding the combustion gases from the combustion chamber into the flueway, said horizontal parts having spaced downwardly extending heat exchange fins facing towards said combustion chamber, and additional heat exchanging members spaced above and offset with respect to said first mentioned heat exchanging members and disposed in the path of the gases directed by said inclined parts.
